UNITED STATES PATENT OFFICE.

LEWIS H. REYNOLDS, OF GOSHEN, NEW YORK.

IMPROVEMENT IN SELF-ADJUSTING TELEGRAPHIC RELAYS.

Specification forming part of Letters Patent No. **82,639**, dated September 29, 1868.

To all whom it may concern:

Be it known that I, LEWIS H. REYNOLDS, of Goshen, in the county of Orange and State of New York, have invented a Self-Adjusting Telegraphic Relay; and I do hereby declare that the following is a full, clear, and exact description of the construction and operation of the same, reference being had to the annexed drawing, making a part of this specification, in which—

a a is a double electro-magnet (composed of soft iron) or two electro-magnets, placed side by side in the helix *b b*, (composed of fine covered copper wire,) the one electro-magnet being stationary, the other, its lower part working on a hinge or pivot at *c c*, and its upper part connected, by a string or rod, *d*, to armature-bar *e* of the common relay—common relay being represented on right-hand side of red line—sufficient space being allowed in helix *b b* to allow one of the magnets *a a* a little play. The helix *b b* is connected, by wires

running underneath, to helix *f f* of common relay, thereby making the helices one continued wire. When an electric current is passing through the wire the positive poles of magnets *a a* being together, they repel, while armature *g* of common relay is attracted to its own magnet, so that the repulsion of one nearly counteracts the attraction of the other, thereby making a self-adjusting relay.

What I claim as my invention, and desire to secure by Letters Patent, is—

The double electro-magnet, or two electro-magnets, placed in a helix or helices, with their like poles near each other, and attachment to armature or armature-bar of common relay, so that their repulsion will counteract, or nearly counteract, the attraction of armature of common relay to its own magnet.

LEWIS H. REYNOLDS.
